UNITED STATES PATENT OFFICE.

HARRY G. WEBSTER, OF CHICAGO, ILLINOIS.

TELEPHONE-RELAY.

1,119,131.

Specification of Letters Patent.

Patented Dec. 1, 1914.

Application filed April 11, 1912. Serial No. 690,148.

To all whom it may concern:

Be it known that I, HARRY G. WEBSTER, a citizen of the United States, residing at Chicago, in the county of Cook and State of Illinois, have invented certain new and useful Improvements in Telephone-Relays, of which the following is a specification.

The present invention relates to relays generally and more particularly to relays for use in telephone systems.

The principal objects of the invention are to provide a relay of this class which shall be (1) compact in structure even though provided with a large number of contacts for the control of a plurality of circuits, (2) cheaper to construct while at the same time providing better electrical contact than the commonly employed relays where platinum is used at the contact points, (3) less liable to gather dust on the contact surfaces and thereby less liable to cause imperfect contacts than relays of the type now commonly employed, (4) provided with contact surfaces so arranged that burning due to sparking will not prevent the establishment of proper circuit relations, as now frequently occurs with relays having platinum contact points.

In carrying out my invention I preferably employ fixed contact strips mounted side by side on edge and provide coöperating wiping contacts which preferably enter the spaces between the contact strips and, by making a wiping engagement with them, establish good electrical connections.

The several features and advantages of my invention will be more fully understood upon reference to the following detailed description taken in connection with the accompanying drawing, and the scope of the invention will be particularly pointed out in the appended claims.

In the drawing, Figure 1 is a side elevation of a relay constructed in accordance with my invention; Fig. 2 is an end elevation of the same showing parts in section taken on a plane indicated by the line 2--2 of Fig. 1; Fig. 3 is a side elevation of a second relay constructed in accordance with my invention in which the resiliency resides in the wiper contact rather than in the coöperating contact strips; Fig. 4 is a plan view of one of the wiper contacts of Fig. 3; Fig. 5 is a plan view of the contact strips with which such wipers coöperate; Fig. 6 is a sectional elevation, on an enlarged scale, of

the contacts of Fig. 3, the section being taken on a plane indicated by the line 6--6 of Fig. 3; Fig. 7 is a side elevation of a third relay constructed in accordance with my invention and illustrating a different armature and contact arrangement; Fig. 8 is a fragmentary side elevation of a fourth relay constructed in accordance with my invention; Fig. 9 is a plan view of the contact arrangement of the relay of Fig. 8; and Fig. 10 shows a modified form of wiping contact. Throughout these views like characters refer to like parts.

Referring to the form of the invention illustrated in Figs. 1 and 2, 10 designates the usual relay winding mounted upon a spool having the heads 11 and connection terminals 12. The core upon which the spool is mounted terminates at one end in a pole face 13, and at the other end in a threaded extension 14, provided with nuts 15, 16 for securing the magnetic angle frame 17 to the core and the assembly relay to the mounting strip. The pole face 13 and the forward end of the angle frame 17 constitute the polar extremities of the relay magnet. The armature 18 is of the usual angular form and rests at its angle upon the knife edge 19, at the forward end of the angle frame 17. The usual screw 20 passing through an opening in the armature into the end of the frame 17, maintains the armature in proper operative position. A spring 21 bears upon the rear end of the angular extension 22 of the armature, to yieldingly hold it out of engagement with, and away from, the pole face 13. The rear end of the spring 21 is slidably supported in the insulating mounting 23 carried upon the frame 17. The rear end of the spring 21 beyond the end of the mounting 23 is provided with a bifurcated up-turned end 24 which embraces a reduced portion of the screw 25, threaded into the rear of the mounting 23. By screwing the screw 25 into and out of the mounting 23 the position of the return spring 21 and its degree of tension upon the armature 18, may be varied. The insulating mounting 23 also carries a number of pairs of spring terminal contacts. Any desired number of such contacts may be employed and in the present instance I have shown eleven pairs 26, 27 and ten pairs 28, 29. As clearly illustrated, the contacts of the former pairs have downwardly extending projections at their outer

ends while the contacts of the latter pairs are not so provided. By this arrangement the lower contact edges of the contact strips are brought into the same horizontal plane 5 and therefore equally distant from their co-operating cylindrical bridging contacts 30 and 31. The rear ends of the contact strips 26, 27, 28, 29, are provided with suitable openings 32, 33 for making the usual wire connections. The several cylindrical bridging contacts 30, 31 are provided with points at their upper ends and heads at their lower ends and are molded into or otherwise secured in the insulating strip 34 mounted 10 upon the upper face of the extension 22 of the armature 18. As illustrated in Fig. 2, the armature is given a sufficient width to accommodate the required number of these bridging contacts.

15 It will be observed that in operation the pulling up of the armature will force the contacts 30 and 31 between adjacent pairs of contacts 26 and 27 in the one case and 28 and 29 in the other. The movement of these bridging contacts 30 and 31 is sufficient to cause their opposite sides to engage the contact strips when the armature is in attracted position. The construction is such that a 20 good wiping contact is obtained between the spring contacts 26, 27, 28, 29 and the co-operating wiping plunger contacts 30, 31. It will be understood that these various contact strips 26, 27, 28, 29 may be connected in circuit in any desired manner. It will also 25 be seen that the several contact springs 26, 27 are substantially L shaped and collectively constitute a bank or rank of contacts overlapping the electro-magnet. The series of wiping contacts 30 may be regarded as 30 forming a second bank or rank of contacts underlying and positioned opposite to the free ends of the contact springs 26, 27. The arrangement is thus one adapted to secure extreme compactness and accuracy of assembly. There are systems of the art in 35 which multiple contact relays are employed; the present relay is available for use in such systems; and the number of contacts and the arrangement of the circuit depends upon the circuits with which the relay is employed.

40 Instead of the solid plunger contacts 30 and 31, I may employ contacts like the contact 35 illustrated in Fig. 10. This contact is made by folding a punching of sheet metal 45 in the manner illustrated. Obviously, other forms of wiping contacts might also be employed.

45 In the form of the invention illustrated in Figs. 3 to 6 inclusive, the spool and winding 50 are the same as before described in connection with the first form of the invention. The angle frame 36 is also similar to the angle frame 17 but terminates into short extensions 37 at its opposite sides between 55 which the armature 38 is pivotally supported

60 by means of pivots such as 39. The extension 44 of the core extends through both the angular frame 36 and the mounting strip 40. A nut 41 holds the parts in position. In this form of the invention a leaf spring 65 70 is secured to the rear end of the extension 43 of the armature 38 and co-operates with an over-hanging hook 44, secured to the frame 36, to return the armature 38 to normal. A screw 45 threaded through the armature 38 and locked in place by lock-nut 46 provides for the adjustment of the air gap between the armature and the pole face 12. In this form of the invention the terminal contacts are in the form of contact strips 75 80 47, 48, 49, 50, 51, 52, 53, 54, 55, 56, rigidly supported throughout their length and secured to the mounting strip 40 by angle plates 57, 58, connected by screws 59 extending through suitable insulating strips 60, 61, 62, 63, 64, 65, and 66 which insulate the contact strips from each other and from the screws and plates. The rear ends of these strips are provided with holes 67 for the purpose of enabling soldered wire connections to be made to them. By this construction these various contact strips are rigidly supported and do not yield as in the case of the corresponding strips 26, 27, 28, 29, of the first form of the invention. In order to 90 95 bring about a wiping engagement, each wiper contact 68 is provided with two contacting ends 69 which are convexly curved, as illustrated in Figs. 4 and 6, so as to readily pass between the co-operating pairs of fixed contacts and establish wiping engagement with them. The wiping contact 68 is secured at its non-contacting end to an insulating mounting 70 which is connected by screws, such as 71, with the rearward extension 43 of the armature 38. By this construction the wiper is insulated from the other parts and serves merely to bridge the co-operating fixed contacts and thereby to establish direct electrical connection between them.

100 It will be understood that, in operation, the pulling up of the armature 38 will move the contacting ends 69 of the wiper 68 out of engagement with the lower contact strips, such as 48 and 49, and into engagement with the upper contacting strips such as, 47, 49, the contact 49 extending opposite both contact 47 and contact 48. Upon retraction of the armature, contact 47—49 will be broken and contact 48—49 closed. It will be apparent that these contact strips may be variously arranged and that the contacting ends of the wipers 68 may be varied in width to suit the position of the co-operating contact strips, and that both may be varied according to the circuit requirements or judgment of the one employing the invention. As viewed in Fig. 6, it will be seen that in the case of wiper contacts 69, the circuit between contacts 48 and 49 is broken 110 115 120 125 130

before the circuit between 47 and 49 is closed. By making the wiper contacts broader as illustrated at 72, the second circuit may be closed before the first is opened and vice versa. Or, again, by replacing the wide strip, such as 49, by two narrow strips, such as 55 and 56, and providing relatively narrow wiper contacts 69, wholly separate and distinct circuits may be controlled. In other words, in the case of contacts 53, 55 and 54, 56, the circuits are wholly separate and independent while in the case of contacts 47, 49 and 48, 49, the circuit always extends through contact 49. This is also true of contacts 50, 52 and 51, 52.

In the form of the invention illustrated in Fig. 7, the winding 73 and spool 73' are similar to those already described; the magnetic angle frame 74 terminates, similarly to the angle frame 36 of the second form of the invention, in extensions 75. The armature 76 is likewise pivoted between the extensions 75 and is provided with a rearward extension 77 which engages the under side of the frame 74 to limit the outward movement of the armature 76. The reduced end 78 of the core extends through the angle frame 74 and the mounting strip 79 and is held in place by a nut 80. A coiled tension spring 81 is secured at one end to the mounting strip 79 and at the other end to the lower end of a strip 82 which is adjustably secured upon the outer face of the armature 76 by screws 83 passing through slots in the strip. By screwing the screws 83 down tight, the strip 82 may be held in any desired position of adjustment. It will be seen that by shifting the strip 82 the effective pull of the spring 81 upon the armature 40 may be varied. In this instance the spring terminal contact strips 84 and 85 are mounted in the insulating member 86, secured to the mounting strip in any suitable way, as by means of the bolts 87 and nuts 88. These strips 84 and 85 have their outer ends shaped and positioned like the strips 26 and 28 of the first form of the invention. In this instance these strips are also arranged in pairs just as in the first form of the invention. 50 But the action of the flat wiper contact 89 is approximately at right angles to that of the wiper contact of the first form of the invention, by reason of the fact that the wiper is mounted at the outer end of the armature 55 instead of on its rearward angular projection. This mounting, as before, may be made in different ways. As shown, the wiper contact 89 is secured to an insulating support 90 which is in turn secured by 60 screws, such as 91, to the end of the armature 76. By this construction the wiper contact 89 is insulated from the armature and serves to bridge adjacent pairs of contacts.

In the form of the invention illustrated in Figs. 8 and 9, the armature 92 is pivoted

between extensions 93 upon the angle frame 94 just as in Fig. 3. A nub 95 on the lower side of the rearward extension 96 of armature 92 serves to limit the outward movement of the armature, occasioned by the return spring 97 riveted at its rear end to the top of frame 94. In this form of the invention the contact springs 98, 99, 100, 101, are mounted side by side on edge in the insulating support 102 and are provided with rearward extensions 103 arranged for soldered or other connections. In the normal position of the relay, the circuits between some of the contact strips are closed and between others open. As shown, the spherical end of wiping contact 104 normally bridges contacts 100, 101 and completes the circuit between them, while that of wiping contact 105 is normally out of engagement with contacts 98 and 99. When the parts are in the attracted position, on the other hand, wiping contact 101 is moved upward out of engagement with contacts 100 and 101 and wiping contact 105 is moved into engagement with contacts 98 and 99 to establish 90 circuit between them. In this form of the invention, the contacts 104 and 105 are suitably mounted in an insulating support 106 secured to the upper face of the extension 96 of the armature 92.

Upon a consideration of the above description taken in connection with the illustration, it will be seen that I have provided a relay by which the various objects enumerated at the beginning of the specification are attained. It will also be apparent that my invention is capable of diverse application and that the same might be employed in relays of many other types and forms than those illustrated and described herein. 100 It will also be apparent that certain alterations and modifications may be made in the different forms of the invention herein disclosed without departing from the spirit and scope of the invention. I therefore do not 110 wish to be unduly limited but aim to cover all such adaptations, alterations and modifications by the terms of the appended claims.

What I claim as new and desire to secure by Letters Patent of the United States is:

1. A multi-contact telephone relay comprising an insulating mounting, a series of flexible contact springs carried at one end by said mounting and extending therefrom side by side forming a bank, said springs individually lying in substantially parallel planes intersecting the plane of the bank, an armature, a magnet structure to actuate said armature secured in compact overlapping relation with said bank and presenting opposite polar extreraties to said armature, and a series of wiping contact members movable in planes intersecting the plane of said bank and actuated responsive to movement of said armature to electrically 120 125 130

- engage the free ends of certain of said springs.
2. A multi-contact telephone relay comprising an insulating mounting, a series of flexible contact springs carried at one end by said mounting and extending therefrom side by side forming a bank, said springs individually lying in substantially parallel planes intersecting the plane of the bank, an armature, a magnet structure to actuate said armature positioned side by side and substantially co-extensive in space with said bank and presenting opposite polar extremities to said armature, and a series of wiping contact members movable in planes intersecting the plane of said bank and actuated responsive to movement of said armature to electrically engage the free ends of certain of said springs.
- 10 3. A multi-contact telephone relay comprising an armature, a magnet structure to actuate said armature and presenting opposite polar extremities thereto, an insulating mounting rigidly related to said magnet structure, a series of flexible contact springs carried at one end by said mounting and extending therefrom side by side forming a bank, said springs individually lying in edgewise relation to said magnet structure, and a series of wiping contact members movable in planes intersecting the plane of said bank and actuated responsive to movement of said armature to electrically engage the free ends of certain of said springs.
- 15 4. A multi-contact telephone relay comprising an armature, a magnet structure to actuate said armature and presenting opposite polar extremities thereto, an insulating mounting rigidly related to said magnet structure, a series of flexible contact springs supported by said mounting in edgewise relation to said magnet structure, said springs collectively forming a bank having overlapping relation with said magnet structure, and a series of wiping contact members movable in planes intersecting the plane of said bank and actuated responsive to movement of said armature to electrically engage the free ends of certain of said springs.
- 20 5. A multi-contact telephone relay comprising an armature, a magnet structure to actuate said armature and presenting opposite polar extremities thereto, an insulating mounting rigidly related to said magnet structure, a series of contact springs carried at one end by said mounting and extending therefrom side by side forming a bank substantially co-extensive with said magnet structure, said springs having free ends flexible in the direction of the plane of the bank, and a series of wiping contact members movable in planes intersecting the plane of said bank and actuated responsive to movement of said armature to electrically engage the free ends of certain of said springs.
- 25 6. A relay structure comprising an electromagnet, an angle frame, an angular armature actuated by said electro-magnet fulcrumed on said frame and having an extension lying in close proximity to said frame, contact springs secured to the rear end of said frame and having their free ends extending forward above said armature extension, said contact springs being also mounted side by side in a plane parallel to said electromagnet and individually occupying planes substantially at right angles to the axis of said armature, and wiping contacts carried by said armature extension and movable under the action of said armature into and out of engagement with adjacent co-operating contact springs.
- 30 7. A multi-contact relay comprising an electro-magnet core and winding, a frame of magnetic material constituting a polar extension of said core, an armature fulcrumed on said frame in operative relation with said core and actuated responsive to current in said winding, an insulating mounting rigidly related to said frame, a series of flexible contact springs carried at one end by said mounting and extending therefrom side by side forming a bank having overlapping relation with said frame and core said springs individually lying in edgewise relation to said frame, and a second series of contact members movable in planes intersecting the plane of said bank and actuated responsive to movement of said armature to make wiping electrical engagement with certain of said springs.
- 35 8. In a multi-contact relay the combination of an armature, an electro-magnet to actuate said armature and presenting opposite polar extremities thereto, an insulating mounting contiguous and rigidly related to said magnet, a series of spring contacts carried at one end by said mounting and extending therefrom side by side forming a bank overlapping said magnet, said contacts individually lying in parallel planes at right angles to the plane of the bank, a series of contacts forming a second bank underlying and positioned opposite to the free ends of said spring contacts and means whereby the attractive movement of said armature will bring contacts of said second bank into wiping electrical engagement with contacts of the first mentioned bank.
- 40 9. In a multi-contact relay the combination of an armature, an electro-magnet to actuate said armature and presenting opposite polar extremities thereto, an insulating mounting contiguous and rigidly related to said magnet, a series of spring contacts carried at one end by said mounting and extending therefrom side by side forming a bank

- bank overlapping said magnet, said contacts individually lying in parallel planes at right angles to the plane of the bank, a series of contacts forming a second bank positioned 5 opposite to the free ends of said spring contacts and an angular extension of said armature overlapping the magnet and actuated on the attractive movement of the armature to bring contacts of said second bank into wiping electrical engagement with contacts of the first mentioned bank.
10. A multi-contact relay comprising a magnet structure, an armature actuated thereby, an insulating mounting rigidly related to said magnet structure, a series of contact springs carried at one end by said mounting and extending therefrom side by side forming a bank having overlapping relation with said magnet structure, said 15 springs being provided at their free ends with angular extensions projecting toward said magnet structure and individually lying in substantially parallel planes intersecting the plane of the bank, and a series 20 of contact members movable in planes intersecting the plane of said bank actuated responsive to movement of said armature to make wiping electrical engagement with said extensions of certain of said springs.
- 25 11. A multi-contact relay comprising a magnet structure, an armature actuated thereby, an insulating mounting rigidly related to said magnet structure, a series of pairs of flexible contact springs carried at 30 one end by said mounting and extending 35
- therefrom side by side forming a bank, said springs individually lying in edgewise relation to said magnet structure, and a series of wiping contacts movable in planes intersecting the plane of said bank and actuated responsive to movement of said armature to engage and oppositely flex the members of certain of said pairs of springs to make wiping electrical engagement therewith and equalize the thrust against said wiping contacts. 40
12. In a multi-contact switch the combination of a magnet structure comprising an electro-magnet and a frame, an insulating mounting rigidly related thereto, a series of 45 flexible contact springs carried at one end by said mounting and extending therefrom side by side forming a bank having overlapping relation with said magnet structure, said springs individually lying in edgewise relation to said magnet structure, an armature actuated by and fulcrumed on said magnet structure, and a series of wiping contact members forming a second bank co-extensive transversely with the first mentioned bank and actuated responsive to movement of said armature to engage certain of said springs. 50
- 55 In witness whereof, I hereunto subscribe my name this 8th day of April, 1912.
- HARRY G. WEBSTER.
